UNITED STATES PATENT OFFICE.

ANTHONY VANDERVELD, OF GRAND RAPIDS, MICHIGAN, ASSIGNEE TO GRAND RAPIDS SHOW CASE CO., OF GRAND RAPIDS, MICHIGAN, A CORPORATION OF MICHIGAN.

ROTARY DISPLAY-RACK.

1,004,605.

Specification of Letters Patent. Patented Oct. 3, 1911.

Application filed February 13, 1911. Serial No. 608,202.

REISSUED

To all whom it may concern:

Be it known that I, ANTHONY VANDERVELD, a citizen of the United States of America, residing at Grand Rapids, in the county of Kent and State of Michigan, have invented certain new and useful Improvements in Rotary Display-Racks; and I do hereby declare the following to be a full, clear, and exact description of the invention, such as will enable others skilled in the art to which it appertains to make and use the same.

My invention relates to improvements in rotary display racks inclosed, and more particularly to such display racks adapted to carry a quantity of hats or other like articles; to support the same movable within a case and conveniently accessible to all and each of the same, and to provide the device with various new and useful features hereinafter more fully described and particularly pointed out in the claims, reference being had to the accompanying drawings in which:—

Figure 1 is a front elevation of a device embodying my invention; Fig. 2 an end elevation of the same with parts broken away; Fig. 3 a plan view of the same; Fig. 4 an enlarged detail of one of the hat supports shown in elevation; Fig. 5 the same in plan view; Fig. 6 an enlarged detail in perspective showing the means for fastening the outer ends of the T-bars to the vertical bars; Fig. 7 an enlarged vertical section of the carriage and a portion of the column; Fig. 8 an enlarged detail in plan view of one of the T-bars showing the post in section; Fig. 9 the same showing a T-bar 7^b in plan view and the tubular column and post in section; and Fig. 10 an enlarged detail in plan view showing means for adjusting the collars 6.

Like numbers refer to like parts in all of the figures.

1 represents a suitable carriage movable toward the front and rear of the case. 2 a bottom to the case above the carriage and having a slot 2^a therein through which projects a support 3 mounted on the carriage and carried thereby in which support is fixed a tubular column 4 extending upward a suitable distance therefrom. In this column is mounted a rotative post 5 reduced

somewhat at 5^a to extend through the slot 2^a and traverse the same, and provided with a hardened center 14 at the bottom resting in a hardened steel plate 15 on the carriage whereby the post is carried upon this center and plate and rendered freely rotative in the column 4. The post extends upward to near the top of the case and on this post is mounted two collars 6, one near the top and the other close above the top of the tubular column. These collars are adjustably fixed on the post 5 by means of two screws 17 spaced apart and engaging suitable plane surfaces 18 formed at right angles to the axis of the screws in the side of the post. By turning these screws a slight rotative adjustment of the collars can be accomplished to bring the T-bar arms 7 cast into the collars, and oppositely projecting therefrom, in the same vertical plane. These arms 7 extend to near the respective ends of the case and attached to the outer ends thereof are vertically disposed flat bars 8 extending from the upper arms 7 downward to near the bottom of the case and parallel with each other. At regular intervals between these arms 7 are horizontally disposed T-bars 7^a extending across between the vertical bars 8 and attached thereto, which bars 7^a are bent laterally as illustrated in Fig. 8 to pass the post 5 and engage one side thereof, the central line of the bars being in the plane of the axis of the post. Each bar 7^a is secured to the post by a clamp 9 bolted to the vertical web of the T-bar. Below the lower arms 7 also at regular intervals are other T-bars 7^b extending across between the vertical bars 8 and secured thereto, which bars 7^b are bent at the middle to extend around one side of the tubular column 4 and out of contact therewith as shown in Fig. 9 whereby they rotate around the same freely. These bars also have a strap 9^a oppositely bent and extending across the opposite side of the tubular column and out of contact therewith to strengthen and stiffen the T-bar. The outer ends of all of these horizontal T-bars are secured to the vertical bars 8 by means of sheet metal plates 11 secured to the bar 8 opposite the end of the T-bar 7 and having lugs turned inward at right angles as at 12

- riveted to the horizontal member of the T-bar, and also having lugs 13 struck up in the lower part embracing the web of the T-bar, as shown in Fig. 6. To variously space 5 apart these horizontal T-bars and use a greater or less number thereof as occasion may require, and to adjust the same, the vertical bars 8 are provided with a series of openings or holes spaced apart at regular 10 intervals in which are inserted screws 11^a whereby the plates 11 are adjustably attached to the bar 8 and can be moved at regular intervals to variously space apart the horizontal T-bars.
- 15 To support the hats or other like articles, the horizontal members of the T-bars are bored close alongside the web at regular intervals and in the holes thus formed are inserted supports formed of wires having 20 their ends 10^a bent downward to extend alongside the vertical web of the T-bar and thence extending in parallel lines, and provided with upwardly inclined portions 10^c and vertically raised or elevated portions 25 10^b. These raised portions enter the crown of the hat and hold the same in place on the wires. The rim of the hat extending clear of the downwardly inclined portions 10^c whereby the hat is not distorted by contact 30 therewith.
- The middle portion of this wire is bent twice at right angles whereby a continuous connecting member 10^d is formed at the outer end of each support, each wire is 35 preferably adapted to support two hats except the outer ones of each horizontal series which are made shorter to permit the whole structure to rotate about the axis of the post when the same is drawn to the forward end 40 of the slot 2^a. By making the holes in the T-bars somewhat larger than the wires, each support can be tilted upward as shown in Fig. 2 to afford more room for inserting and removing the hats on the next support 45 below.
- The operation of my device is obvious from the foregoing description; the carriage being moved to the front of the case brings the column and rotative post in position to 50 permit the post together with the rack supported thereby to rotate freely within the case. The rack can thus be turned to gain access to any part of the same and bring either side thereof outside the case. If de- 55 sired a greater or less number of T-bars may be used by spacing the same apart differently and securing the same to the respective outer vertical bars 8 in proper position.
- What I claim is:—
- 60 1. A display rack, comprising a rotatable post, horizontally disposed T-bars carried by the post, each having a series of openings near the web and supports consisting of wires bent at the end to enter said openings

and laterally engage the web of the bars, 65 and also extending laterally from the T-bars.

2. A display rack, comprising a rotatable post, T-bars extending horizontally from the post and carried thereby, vertically disposed bars attached to the outer ends of the 70 T-bars, intermediate T-bars attached to the vertical bars at their respective ends, and wire supports inserted in openings in the T-bars and extending laterally therefrom.

3. A display rack, comprising a rotatable 75 post, collars on the post, oppositely projecting T-bars inserted in the collars, two set screws in one of the collars spaced apart and parallel, said screws also engaging flat surfaces on the post arranged at right angles 80 to the screws, vertical bars attached to the outer ends of the T-bars, other T-bars attached to the vertical bars and bent to engage one side of the post, clamps on the last named T-bars engaging the other side of the 85 post and supports extending laterally from the T-bars.

4. A display rack, comprising a rotatable post, a tubular column in which the lower part of the post is rotative, collars on the 90 post above the column and spaced apart, T-bars extending horizontally and oppositely from the collars, vertically disposed bars attached to the outer ends of the T-bars and extending downward opposite the column, other T-bars attached at intervals to the vertical bars, those extending across the post being bent to engage one side thereof and clamped thereto, and those extending across the column being bent opposite the 100 same and out of contact therewith, and supports mounted on the T-bars and extending laterally therefrom.

5. A display rack, comprising a horizontally disposed series of superposed T-bars 105 spaced apart and each having openings therein close to the vertical web, and wire supports of less diameter than the openings bent downward at the ends to enter said openings and laterally engage the web of 110 the bar to hold the support horizontally extended from the bar and also to permit the support to be lifted at its free end.

6. In a display rack, a T-bar having openings near the web, and a wire hat support 115 having its ends bent downward and inserted in said openings and laterally engaging the web of the bar and also having its side portions bent upward to form raised portions to enter the crown of a hat and hold the 120 same in place on the support.

7. In a display rack, a horizontally disposed T-bar, a vertically disposed flat bar, a plate secured to the flat bar and having lugs bent at right angles and riveted to the 125 head of the T-bar and also having other lugs struck up at each side of the web of the T-bar.

8. A display rack, comprising a rotatable post, oppositely projecting horizontal T-bars carried by the post, vertically disposed flat bars attached to the outer ends of the T-bars and having openings at intervals, other T-bars extending between the vertical bars, plates attached to the ends of the last named T-bars and fastenings to secure the

plates to the vertical bars adjustable in said openings. 10

In testimony whereof I affix my signature in presence of two witnesses,

ANTHONY VANDERVELD.
